[57] CLAIM

The ornamental design for a liquor dispenser, as shown and described.

DESCRIPTION

FIG. 1 is a front perspective view of a liquor dispenser showing my new design;

FIG. 2 is a front elevational view thereof, the broken line showing of the liquor bottles being for illustrative purposes only;

FIG. 3 is a rear elevational view thereof;

FIG. 4 is a side view in elevation with the opposite side being a mirror image thereof;

FIG. 5 is a bottom view; and,

FIG. 6 is a top view.
